UNITED STATES PATENT OFFICE.

FRED M. LYON, OF PONTIAC, ILLINOIS.

CORN-GRINDER.

1,350,261.

Specification of Letters Patent. Patented Aug. 17, 1920.

Application filed October 19, 1916. Serial No. 126,604.

To all whom it may concern:

Be it known that I, FRED M. LYON, a citizen of the United States, residing at Pontiac, in the county of Livingston and State of Illinois, have invented certain new and useful Improvements in Corn-Grinders; and I do hereby declare the following to be a full, clear, and exact description of the invention, such as will enable others skilled in the art 10 to which it appertains to make and use the same.

This invention relates to grinding mills and more especially to those employing a cone and a shell of hard cast metal; and an 15 object of the same is to produce an improved grinder for use especially on soft corn and corn cobs. I have discovered that when some materials, and more especially corn on the cob while soft, as is the case well up into the 20 spring, are ground in a mill whose co-acting metal faces have burs or ridges with grooves between them, the ground materials, by reason of the oil in the germ of the grain, especially in new or soft corn, and on account 25 of the character of cobs which, when soft, ordinarily contain an abundance of moisture or oils, adhere more strongly to the faces when they are of rough, hard metallic casting and quickly fill up the grooves so that the 30 grinding elements move over each other without results. Experiments have shown that such materials, including the oil therein, adhere much more strongly to cast and hardened metallic surfaces of burs than to 35 stone surfaces. Efforts to avoid or to overcome this difficulty have been made along the lines of changing the material of the elements, altering their relative position and speed and direction of rotation, deepening 40 and changing the shape and direction of the grooves, and enlarging and changing the shape and direction of the ridges; but, as the difficulty persisted after these experiments had been made singly and collectively, I was 45 forced to the conclusion that it was the nature of the faces of the metal over the ridges and in the grooves, more than the shape of either of the latter, that produced the adhesion of the ground cobs. I may say 50 that to an extent also the same difficulty is found in other materials which are ground, but as it is more prevalent in corn and cobs, I refer more especially thereto herein.

I have noticed that this difficulty was not 55 so pronounced with older machines, despite the fact that these may be quite dull; yet

when they are sharpened the difficulty was hardly apparent. So I have been forced to the conclusion which I have verified by experiment, that it is the roughness of the 60 faces of the castings, more especially iron castings, which has its effect on the ground material and causes the choking up of the grooves. I therefore grind or polish said faces of hard cast metallic burs throughout 65 before setting the machine to work at all, and the result is that the "pulp" if we may call it such passes much more freely through the mill and the work of the same is expedited to a large degree, by reason of 70 the resulting elimination of the tendency to corrosion and retention of components of the material under treatment.

The following specification describes the invention as applied to a popular form of 75 such mills, but I do not wish to be limited in that respect.

Referring to the accompanying drawings:

Figure 1 is a plan view of the conical shell.

80

Fig. 2 is a plan view of the co-acting face of the cone which is intended to be rotated within said shell.

Fig. 3 is a section through the shell on about the line 3—3 of Fig. 1, showing the 85 face of one arc thereof on an enlarged scale.

While the relative position of the shell and cone may be varied to suit the type of mill to which they are applied, both the shell S and the cone C in the present case 90

are of rough iron castings, with their meeting or working faces provided with oblique and therefore effectively spiral paths P which are nearly flat toward the small end of these elements and slightly tangential 95 thereto, and which paths fade away or merge into a single circle at the larger end of each element, leaving decided burs or angles A at the outer corners of the paths. In the faces of these paths beginning near the small end 100 of each element are formed grooves G which extend thence to the circle at the larger end of the element, and in the ridges of these grooves beginning yet nearer said circle are formed smaller or sub-grooves G' which extend thence to said circle and divide the ridges at this end of each element. Such is my preferred manner of forming the elements of the mill, one being the female and the other male, and as is well-known they 110 are nested, and one is held fixed while the other is rotated, or both may be rotated if

desired. These paths and grooves may be formed in the act of casting the elements, or in doing so they may be shaped and afterward finished by grinding; but the present 5 invention consists in grinding into the grooves and upon the faces of all ridges to such an extent that they may be said to be polished, and this polishing is done before the mill is set to work at all.

10 I wish to distinguish between "polishing" and "grinding." By the latter term as employed herein I mean such grinding as may be used to form or to deepen the grooves and therefore to form or to shape up the ridges, 15 but which does not remove the roughness that is left in iron castings. By the term "polishing" I desire to be understood to cover the grinding of the surfaces of the ridges and also the bottoms of the grooves 20 to such an extent and in such a manner that all the rough or pitted surfaces on the grinding faces of the burs are highly polished—much the same as they appear in a mill after it has been used for a long time. This 25 polishing is done by a special corundum wheel in a special manner forming no part of the present invention, but I have found that a grinding machine so treated as to remove as far as reasonably practicable all 30 fine obstructions which would be likely to retain or hold any moist or oily product from the cast hard metallic working faces of the burs before it is put to work does not possess the objections first stated above.

35 What I claim is:

1. A cast metal grinding element for

grinding soft grain and cobs, having a grinding surface inclined to the axis of the element, the grinding surface being provided with relatively large spaced inclined ridges 40 decreasing in depth from the feed toward the discharge ends, the surface of the grinding element between said ridges being grooved to form lesser ridges, all the ridges having sharp cutting edges, and the operative surface of the element, including all the ridges and depressed surfaces, being ground and polished throughout.

2. A cast metal grinding element for grinding soft grain and cobs, having a grinding 50 surface inclined to the axis of the element, the grinding surface being provided with relatively large spaced inclined ridges decreasing in depth from the feed toward the discharge ends, the surface of the grinding 55 element between said ridges being grooved to form lesser ridges, all of said ridges being formed with increased spacing between the ridges from the feed toward the discharge ends thereof, all the ridges having 60 sharp cutting edges, and the operative surface of the element, including all the ridges and depressed surfaces, being ground and polished throughout.

3. A grinding mill for soft grain and cobs 65 including a coacting cone and shell, each having a surface such as specified in claim 1, the ridges of the cone and the shell being oppositely inclined.

In testimony whereof I affix my signature 70 in presence of two witnesses.

FRED M. LYON.
